PINE STEM OR SIMILAR ARTICLE

William Clark Taylor, Washington, D. C.

Application March 4, 1957, Serial No. 45,082

Term of patent 14 years

(Cl. D85—8)

Fig. 3

Figure 1 is a perspective view of a pipe stem or similar article, showing my novel design;

Figure 2 is a fragmentary side elevational view; and

Figure 3 is an enlarged fragmentary top plan view thereof.

The broken line showing of a pipe bowl in Figure 1 is for purpose of illustration only.

I claim:

The ornamental design for a pipe stem or similar article, as shown and described.
